J. M. HANSON

CAN PUNCH

Filed Aug. 11, 1922

Inventor:
JOHN MARTIN HANSON
By Hazard & Miller
Attorneys.

UNITED STATES PATENT OFFICE.

JOHN MARTIN HANSON, OF LOS ANGELES, CALIFORNIA.

CAN PUNCH.

Application filed August 11, 1922. Serial No. 581,139.

To all whom it may concern:

Be it known that I, JOHN MARTIN HANSON, a citizen of the United States, residing at Los Angeles, in the county of Los Angeles and State of California, have invented new and useful Improvements in Can Punches, of which the following is a specification.

My invention relates to tools for punching condensed milk cans and the like, and a purpose of my invention is the provision of a can punch of extremely simple, inexpensive and durable construction by means of which a can may be effectively punched to form an opening through which the contents of the can can be discharged, and without the possibility of the tool contaminating the contents of the can.

Although I have herein shown and described only one form of can punch embodying my invention, it is to be understood that various changes and modifications may be made herein without departing from the spirit of the invention and the spirit and scope of the appended claim.

In the accompanying drawings,

Figure 1 is a view showing in perspective one form of can punch embodying my invention.

Fig. 2 is a fragmentary view of the tool in punching position with respect to a can.

Referring specifically to the drawings in which similar reference characters refer to similar parts, my invention, in its present embodiment, comprises a shank 15 formed of metal or other suitable material, and which is shown as round in cross section, although it is to be understood that it may be of any cross sectional contour desired.

One end of the shank carries a handle 16 of spherical form and preferably constructed of wood. The opposite end of the shank is provided with an extension of reduced thickness which constitutes a penetrating prong 17. This prong is, preferably of circular form in cross section and is tapered from its point of connection with the shank to its free end so as to provide a relatively sharp point at its free end. At the junction of the shank and the prong, an annular shoulder 18 is provided, such shoulder constituting a member for limiting the inward movement of the prong within a can.

In the applied position of the tool as clearly shown in Fig. 2, the prong 17 is adapted to be forced through the top of the can 19 and it will be understood that in order to obtain this effect, it is necessary to exert downward pressure upon the punch through the medium of the handle 16. The shoulder 18 obviously abuts the can top to limit the inward movement of the prong 17, and in practice the prong is made relatively short so that the possibility of its contacting with the contents of the can is prevented. This naturally prevents the contamination of the contents by the punch.

What I claim is:

A can punch comprising a shank having a spherical handle on one end and having the other end reduced in cross section and extended to provide a pointed prong and a limiting shoulder at the junction of the shank and prong.

In testimony whereof I have signed my name to this specification.

JOHN MARTIN HANSON.
